HEDDLE FRAME

Filed Jan. 28, 1932

Inventor:
Louis Strohacker,
By Charles O. Shervey
Attorney.

UNITED STATES PATENT OFFICE

LOUIS STROHACKER, OF FREEPORT, ILLINOIS, ASSIGNOR TO STRUCTO MANUFACTURING COMPANY, OF FREEPORT, ILLINOIS, A CORPORATION OF ILLINOIS

HEDDLE FRAME

Application filed January 28, 1932. Serial No. 589,839.

This invention relates to heddle frames for looms, and its principal object is to provide simple and efficient means for attaching and locking the heddles to the frame.

Another object is to provide novel means whereby any number of the heddles may be quickly detached from the frame or others added to those already carried thereby.

With these and other objects and advantages in view, this invention consists in the several novel features of construction, arrangement and combination of parts herein-after fully set forth and claimed.

The invention is clearly illustrated in the drawing accompanying this specification in which—

Figure 1 is a side elevation of a heddle frame embodying a simple form of the present invention, and illustrating a number of heddles attached thereto, the heddle frame being shown in connection with a fragment of the framework of a loom;

Fig. 2 is a side elevation of the heddle frame and heddles illustrating the manner of disconnecting the locking bars from the frame;

Fig. 3 is a view similar to Fig. 2, illustrating the manner of removing or replacing any of the heddles;

Fig. 4 is a detail vertical cross section taken on the line 4—4 of Fig. 1; and

Fig. 5 is a detail vertical cross section taken on the line 5—5 of Fig. 1.

Referring to said drawing, the reference character 6 designates a fragment of the framework of a loom of ordinary construction, and 7, 7 designates upright guides or channels in which the heddle frames are guided for vertical movement.

The heddle frame comprises upper and lower horizontal frame bars 8 and upright frame bars 9 extending between the ends thereof and spot welded or otherwise secured thereto to form a rectangular frame. To the upper horizontal frame bar 8 are secured loops or eyes 10 in which are removably secured the bent ends of a bail 11 which is connected by suitable means to operating mechanism for separating the heddle frames, but as this mechanism forms no part of the

present invention, it will not be necessary to describe the same. The upright frame bars 9 are desirably channel shaped or U-shape in cross section, the side webs 12 of which overlap the upper and lower bars 8 and are spot welded thereto, and the U-bends 13 of which are slotted at their upper and lower ends as at 14 and 15.

Removably held in the slots 14 and 15 are upper and lower heddle locking bars 16 and 17, one of which has interlocking connections with the upright frame bars, and for this purpose is provided with notches 18 adjacent its ends adapted to engage over the edges of the associated slots 14 in the upright frame bars 9. The heddles 19 are formed with slots adjacent their upper and lower ends through which the locking bars 16 and 17 extend, and, in accordance with common practice, are also provided with eyes 20 intermediate their ends through which the warp threads are threaded.

It will be observed that the interlocking connections between the upper locking bar 16 and upright frame bars 9 prevent endwise movement of said locking bar, and that when the lower locking bar is held in the slots 15 with the heddles attached to the locking bars, the upper locking bar cannot be raised to disconnect the notched portions from the upright frame bars. When the heddle frame is in place in the guideways 7, endwise movement of the lower locking bar 17 is prevented by the bottoms of the guideways, consequently, the heddles and locking bars are held against disconnection from the heddle frame.

To remove or replace any of the heddles, the bail 11 is detached from the heddle frame, the latter withdrawn from the guideway 7 and the lower locking bar 17 withdrawn from one of the slots 15, whereupon the corresponding end of the upper locking bar 16 may be raised sufficiently to disengage the notched portion 18 from the edge of the slot 14. With the heddles occupying a grouped position at the middle of the locking bars or disposed adjacent the free ends thereof, the locked end of the upper locking bar may be raised to disengage the notched part from the edge of the associated

slot and the upper locking bar may then be slid back, thus withdrawing its opposite end from the associated upright frame bar, as seen in Fig. 3, thereby permitting any of the 5 heddles to be detached from or others attached to the locking bars. The heddle 19, shown by the dotted lines, in Fig. 3, illustrates the position of one of the heddles about to be attached to the locking bars.

10 To lock the heddles to the frame, the free end of the upper locking bar is inserted into the slot 14 and both notches re-engaged with the edges of the slots, the free end of the lower locking bar being then inserted into the 15 slot 15. It will be observed that as long as the lower locking bar is held in the lower slots, the upper locking bar cannot be raised or disconnected from the upright frame bars, and, as a consequence, the heddles are locked 20 to the frame.

I claim as new, and desire to secure by Letters Patent:

1. A heddle frame in which is comprised a rectangular frame, horizontal upper and 25 lower locking bars, one of which has interlocking connections with the frame and the other of which has a sliding connection therewith, and heddles removably attached to said locking bars and co-operating therewith to 30 maintain said interlocking connection between the locking bar and frame.

2. A heddle frame in which is comprised horizontal upper and lower frame bars, upright end frame bars rigidly secured thereto 35 to form a rectangular frame, said end frame bars having oppositely disposed slots at their upper and lower ends, horizontal upper and lower locking bars, heddles attached to said locking bars, one of said locking bars extending 40 through two oppositely disposed slots in the end frame bars and having interconnections therewith, and the other locking bar extending through the other two oppositely disposed slots and acting through 45 the heddles to hold the other locking bar against disconnection from the frame.

3. A heddle frame in which is comprised horizontal upper and lower frame bars connected at their ends by upright end frame bars, said end frame bars having oppositely 50 disposed slots adjacent their upper and lower ends, horizontal upper and lower locking bars, heddles having slots at their ends through which said locking bars extend, one 55 of said locking bars being formed with notches adjacent its ends adapted to engage with the edges of two opposite slots in the end frame bars, and the other locking bar being arranged to extend into the other opposite slots of the upright frame bars, whereby to hold the notches of the notched locking bar in engagement with the end frame bars 60 through the heddles.

4. A heddle frame in which is comprised 65 horizontal upper and lower frame bars, up-

right end frame bars rigidly secured thereto to form a rectangular frame, said end frame bars being of channel formation and having oppositely disposed slots at their upper and lower ends, horizontal upper and lower locking bars, heddles attached to said locking bars, one of said locking bars extending through two oppositely disposed slots in the end frame bars and having interconnections therewith, and the other locking bar extending through the other two oppositely disposed slots and acting through the heddles to hold the other locking bar against disconnection from the frame.

5. A heddle frame in which is comprised 80 horizontal upper and lower frame bars connected at their ends by upright end frame bars of channel formation, said end frame bars having oppositely disposed slots adjacent their upper and lower ends, horizontal upper and lower locking bars, heddles having 85 slots at their ends through which said locking bars extend, one of said locking bars being formed with notches adjacent its ends adapted to engage with the edges of two opposite slots in the end frame bars, and the other locking bar being arranged to extend into the other opposite slots of the upright frame bars, whereby to hold the notches of the notched locking bar in engagement with 90 the end frame bars through the heddles.
